(57) **CLAIM**

The ornamental design for a display screen with animated graphical user interface, as shown and described.

DESCRIPTION

FIG. 1 is a front view of a display screen with animated graphical user interface showing a first image of my new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is an enlarged view of the area 8 indicated by the single dot-dash broken lines in FIG. 1;

FIG. 9 is an enlarged view of the area 9 indicated by the single dot-dash broken lines in FIG. 2;

FIG. 10 is an enlarged view of the area 10 indicated by the single dot-dash broken lines in FIG. 3;

FIG. 11 is an enlarged view of the area 11 indicated by the single dot-dash broken lines in FIG. 4;

FIG. 12 is an enlarged view of the area 12 indicated by the single dot-dash broken lines in FIG. 5;

FIG. 13 is an enlarged view of the area 13 indicated by the single dot-dash broken lines in FIG. 6; and,

FIG. 14 is an enlarged view of the area 14 indicated by the single dot-dash broken lines in FIG. 7.

The appearance of the animated graphical user interface sequentially transitions between the images shown in FIGS.

1-7. The process or period in which one image transitions to another image forms no part of the claimed design. The evenly-spaced broken lines depict portions of the display screen with animated graphical user interface that form no part of the claimed design. The areas indicated by the single dot-dash broken lines shown in FIG. 1, FIG. 2, FIG. 3, FIG. 4, FIG. 5, FIG. 6, and FIG. 7 illustrate the boundary of
